WALTER E. COFFIN, OF CLEVELAND, OHIO, ASSIGNOR TO THE NATIONAL MALLEABLE CASTINGS COMPANY, OF CLEVELAND, OHIO, A CORPORATION OF OHIO.

UNCOUPLING-ROD FOR CAR-COUPINGS.

1,012,986.

Specification of Letters Patent.

Patented Dec. 26, 1911.

Application filed July 6, 1910. Serial No. 570,680.

To all whom it may concern:

Be it known that I, WALTER E. COFFIN, of Cleveland, Cuyahoga county, Ohio, have invented a new and useful Uncoupling-Rod 5 for Car-Couplers, of which the following is a full, clear, and exact description, reference being had to the accompanying drawings, forming part of this specification, in which—

10 Figure 1 is an end view showing a portion of a car sill with my improved uncoupling rod applied thereto; Fig. 2 is a side view of the same; and Figs. 3 and 4 are end and side views respectively showing a modification.

15 My invention has relation to uncoupling rods for car couplers, and is designed to provide a rod having its operating handle or handles so arranged that they will drop 20 back into their normal position, hanging substantially straight down whether the inner end of the rod is raised or not.

25 In some forms of couplers, when the parts are in lockset or in knuckle-thrown position, it quite often happens that the locking mechanism is in such position that the uncoupling rod which operates it cannot rotate or fall backwardly into its normal position again. In the case of a continuous rod with 30 a depending handle integral with its outer end, this handle will then stick outwardly at an angle to the end sill of the car. This is a source of constant danger to trainmen, since, in spite of the automatic action of the 35 coupler, they quite often pass between the cars and pull the knuckle open by hand after the lock has been raised sufficiently to permit this. After the coupler has been opened, its connection with the uncoupling 40 rod is such that the rod cannot rotate backwardly to normal position; and there is danger that the trainmen may get caught by the projection of the handle and not get out from between the rails in time. My invention overcomes this objection in a simple and efficient manner.

45 Referring first to the form of my invention shown in Figs. 1 and 2, the numeral 2 designates a transversely extending uncoupling rod, which is rotatably supported in suitable brackets 3 attached to the end sill 4. The inner end of this rod, or in the case of a rod which extends wholly across the car so as to be operated from both sides, its 50 central portion has a suitable link and

clevis connection 5 with the coupling pin or lock 6 of the coupler head 7. The outer end of the rod 2 is bent downwardly, as shown at 8, and thence inwardly in a direction substantially parallel with the body portion of 60 the rod, as shown at 9. 10 designates the handle, which is provided with an eye 11 at its upper end loosely threaded upon the body portion of the rod 2. The handle passes downwardly behind the portion 9 so that 65 when an outward pull is given to this handle it will engage the portion 9 and rotate the rod to raise the pin or lock. The bends 8 and 9 need not be completed before the rod is assembled on the car, inasmuch as these 70 bends may be too abrupt to allow the slipping on of the loose-handle member; but the end portion of the rod may be left partially or wholly straight; and after the rod has been placed in the brackets and the 75 handle member threaded thereon, the bend is completed.

80 While I have shown only one end portion of the rod 2, it will be understood that a similar handle device may be provided at each end thereof so as to permit the coupler to be operated from both sides of the car.

85 In the modification shown in Figs. 3 and 4, the handle member 12 is provided with a horizontally extending handle portion 13 at its lower end. In order that this handle portion shall not tip inwardly out of horizontal line, its upper end portion is formed into two spaced eyes 14, which are threaded upon the rod 2^a at opposite sides of the bearing bracket 3^a. The bracket 3^a is preferably of the kind having a separable eye-portion 3^b; and in assembling the parts, the handle portion with its eyes properly formed is first slipped on the rod 2^a, and the separable member 3^b of the bracket is engaged with the rod between the said eyes, after which the whole device is applied to the car by engaging the member 3^a with the base portion of the bracket which has been previously attached to the end sill. The double right-angled bend or bends in the transverse rod may then be made cold, while the rod is in position on the car. An outward pull upon the handle portion of the handle member will rotate the transverse rod in the same manner as in the form first described.

100 While I have shown my invention as applied to a coupler of the top-operating type, 110

it will be obvious that it may be applied to couplers of the bottom-operating type; that the uncoupling rod may be connected with the coupling pin or lock in any suitable way; and that various other changes may be made in the details of construction and arrangement of the parts without departing from the spirit and scope of my invention as defined in the appended claims.

10 What I claim is:—

1. An uncoupling rod for car couplers, having an end portion bent reversely back substantially parallel to the body portion of the rod, and a handle member having an eye loosely engaging the body portion of the rod adjacent to the bend, said member

extending downwardly behind the bent end; substantially as described.

2. An uncoupling rod for car couplers, having an end portion bent reversely back 20 substantially parallel to the body portion of the rod, and a handle member having two spaced eyes loosely engaging the body portion of the rod adjacent to the bend, said member extending downwardly behind the 25 bent end; substantially as described.

In testimony whereof, I have hereunto set my hand.

WALTER E. COFFIN.
